(57) **CLAIM**

The ornamental design for a percussive massage device, as shown and described.

DESCRIPTION

FIG. 1 is a front, right side perspective view of a percussive massage device showing my present design; FIG. 2 is a rear, right side perspective view thereof; FIG. 3 is a front view thereof; FIG. 4 is a rear view thereof; FIG. 5 is a left view thereof; FIG. 6 is a right view thereof; FIG. 7 is a top view thereof; and, FIG. 8 is bottom view thereof.

The broken lines in the drawings illustrate portions of the percussive massage device which form no part of the claimed design.
